PENNSYLVANIA.

TIE-PLATE.

1,381,575.

Specification of Letters Patent. Patented June 14, 1921.

Application filed February 21, 1921. Serial No. 446,834.

To all whom it may concern:

Be it known that we, JOHN LUNDIE and GEORGE W. WHITEMAN, both citizens of the United States, residing at New York, New York, and Philadelphia, Pennsylvania, respectively, have invented certain new and useful Improvements in Tie-Plates, of which the following is a specification.

This invention relates to tie-plates for railway rails, the plate preferably being constructed and designed for use with the continuous type of rail-joint so that it will lie under the abutting ends of the rails, with the joint bars interposed between said rail ends and the tie-plate; although the tie-plate may also be placed at other locations where a continuous rail-joint is not used.

One of the objects of the present invention is to provide a tie-plate of such construction as will give a proper seat or support for the joint upon the tie. In a measure, the present invention makes use of some of the principles found in prior Reissue Letters Patent of John Lundie, No. 14,124, dated May 2, 1916. Another object of the present invention is to provide a tie-plate of that type in which the top-seating surface thereof is inclined so as to be normal to the line of thrust of the coning of the car-wheels, which tie-plate is provided with special means adapted for association with the continuous type of rail-joint. Other objects of the invention are to provide an efficient and practical tie-plate which has, at its top, means adapted to receive lateral thrust.

These being among the objects of the present invention, the same consists of certain features of construction and combinations of parts to be hereinafter described and then claimed with reference to the accompanying drawings illustrating one embodiment of the invention, and in which:

Figure 1 is a plan view of the tie-plate, with which "the continuous joint" may be employed to connect the adjacent ends of two rails.

Fig. 2 is an edge view of the plate;

Fig. 3 is an elevation viewed toward the thinner edge of the tie-plate, and

Fig. 4 is a transverse section of the plate, the said joint and a rail, the tie being shown in side elevation.

In the drawings, two rails, of which rail

10 is shown, are connected by means of joint 55 bars 12, 13 of suitable cross section, said joint bars having mutually presented base-flanges 14, 15, upon which the bases of the two rails rest. The tie 16 may be any usual wooden tie.

Our improved tie-plate, which may be used in association with such joint bars as 12, 13, comprises the plate proper 17, preferably having on its bottom or base a plurality of tie-engaging elements, preferably 65 such as are shown and described in aforesaid patent. Means are provided so that the lateral thrust may be imparted to the tie-plate, and preferably, such means consist of a longitudinal rib or shoulder 18, which is 70 located at approximately the mid-width of the tie-plate 17 and extends from end to end.

The tie-plate when used with "the continuous joint" is positioned thereunder and seated upon the tie, with the thrust-receiving shoulder or rib 18 positioned between the base-flanges 14, 15 of the joint bars 12, 13, so that the adjacent edges of said flanges will span the said shoulder. When the parts are bolted and spiked, the lateral thrust is transmitted to the rail, and thence to the joint bars, and will be transmitted laterally to the shoulder 18 intermediate of the joint bars. The tie-plate need have no outer shoulder such as the edge of a rail would ordinarily 80 abut against if the joint bars were not used. Preferably, said tie-plate 17 is provided with a slight camber longitudinally thereof, and which may provide not only a concaved transverse base for the plate, but a convex 85 transverse top. Preferably, the radius of curvature of the described camber is about 10 feet, as this curvature in practice has been found to be probably the best suited for the particularly described tie-engaging elements 90 on the tie-plate.

Preferably—although not necessarily—the upper surface of the tie-plate is inclined as above mentioned, and in such cases it is preferred that the tie-engaging elements upon 100 the base of the tie-plate be constructed as shown, that is to say, its under surface will have a plurality of seating surfaces which are spaced apart, said surfaces being indicated at 19, 20, 21, 22 and 23. These seating 105 surfaces, in the preferred embodiment of the invention, extend throughout the length of the tie-plate, and are disposed in planes

parallel with each other, are arranged in planes extending at acute angles to the supporting surfaces of the ties, and are also parallel, substantially, with the upper surfaces of the heads of the rails and with the bases of the joint bars 12, 13. These surfaces are arranged, as shown, with a plurality of steps, the steps being joined preferably by reverse curves forming shoulders which are convex at 24, being the lowest level of the undersurface of the base of the tie-plate, and which are concave at 25, being the highest level of the undersurface.

In the specifically described and illustrated embodiment of the invention it will be seen that the tie-plate will gradually form its own seat in the ties without injury to the fibers of the ties; that the described combination of parts will practically eliminate all outward thrust due to the coning of the wheels, for the reason that in the specific embodiment of the invention all bearing surfaces will be normal to the line of thrust of the coned car-wheels or wheel load; and, that if the tie-plate be cambered as described, it will have more or less of a springy action, to permit it to be flattened out as the load passes over it, the plate assuming its camber when the load is removed, until the tie ultimately assumes a convexity corresponding to the concavity of the plate.

Spike-holes 26 are preferably made in the tie-plate, so as to coincide with the spike-holes usually made in the ends of the joint-bars.

Obviously, the invention described and illustrated is susceptible of modification, and this may be resorted to by those skilled in the art without departing from the scope of the claims.

What we claim is:

1. The combination with a tie-plate having an upper thrust-receiving shoulder positioned in the zone thereof, over which the rail is to be positioned, of rail-joint bars applied to said plate with the inner edges of their bases spanning said shoulder.

2. The combination with a rail, and joint-bars applied to said rail, of a tie-plate having an upper shoulder, the inner flanges of said joint-bars being between the rail and tie-plate, and said shoulder being between the adjacent edges of said flanges to take up lateral thrust.

3. The combination with a tie-plate having an upper thrust-receiving shoulder positioned in the zone thereof over which the rail is to be positioned, of rail-joint bars applied to said plate with the inner edges

of their bases spanning said shoulder, said plate being also cambered longitudinally.

4. The combination with a tie-plate having an upper thrust-receiving shoulder positioned in the zone thereof, over which the rail is to be positioned, of rail-joint bars applied to said plate with the inner edges of their bases spanning said shoulder, the base of said plate having a plurality of tie-engaging elements.

5. The combination with a tie-plate having an upper thrust-receiving shoulder positioned in the zone thereof, over which the rail is to be positioned, of rail-joint bars applied to said plate with the inner edges of their bases spanning said shoulder, the base of said plate having a plurality of longitudinal tie-engaging surfaces disposed in different planes.

6. The combination with a rail, and joint-bars applied to said rail, of a tie-plate having an upper shoulder, the inner flanges of said joint-bars being between the rail and tie-plate, and said shoulder being between the adjacent edges of said flanges to take up lateral thrust, said tie-plate having a joint-bar seat normal to the line of thrust of the coning of a car-wheel and lower surfaces parallel with said seat.

7. The combination of a tie-plate, rail-joint bars resting upon said plate, and thrust-receiving means on the plate and between adjacent surfaces of the joint bars.

8. The combination of a tie-plate, rail-joint bars resting upon said plate, and thrust-receiving means integral with said plate and spanned by and between the adjacent surfaces of the joint bars.

9. The combination of a tie-plate, a rail-joint bar, and means located on the plate and at the inner edge of the bar for taking up lateral thrust of the bar.

10. The combination of a tie-plate, rail-joint bars resting upon said plate, and means located between the bars for transmitting the lateral thrust of the bars to the tie-plate.

11. The combination of a cambered tie-plate, rail-joint bars resting upon said plate, and means located between the bars for transmitting the lateral thrust of the bars to the tie-plate.

12. The combination of a tie-plate having an inclined upper surface, rail-joint bars resting upon said plate, and means located between the bars for transmitting the lateral thrust of the bars to the tie-plate.

JOHN LUNDIE,
GEORGE W. WHITEMAN.
